FRANK B. WILDMAN AND GEORGE LAWSON BALLARD, OF NORRISTOWN, PENNSYLVANIA, ASSIGNEES TO WILDMAN MFG. CO., A CORPORATION OF PENNSYLVANIA.

STOP MECHANISM FOR KNITTING-MACHINES.

1,144,273.

Specification of Letters Patent. Patented June 22, 1915.

Application filed March 7, 1913. Serial No. 752,797.

To all whom it may concern:

Be it known that we, FRANK B. WILDMAN and GEORGE LAWSON BALLARD, the former a citizen of the United States and the latter 5 a subject of the King of Great Britain, both residing at Norristown, Pennsylvania, have invented certain new and useful Improvements in Stop Mechanism for Knitting-Machines, of which the following is a specification.

The invention concerns in its best application a let-off particularly adapted for use in connection with the "dogless" form of fixed cylinder and dial circular knitting machine, such, for instance, as is shown in Letters Patent of the United States, granted to G. L. Ballard #1012966, December 26, 1911, though it will be understood that some 15 features of our invention may be applied to other types of machines.

One object of our invention is to provide a let-off which will operate to stop the machine when either the overhead stop motion or the needle detector is operated.

The invention consists in the features and combination and arrangement of parts hereinafter described and particularly pointed out in the claims.

In the accompanying drawings Figure 1 is a front view of a circular knitting machine, of the dogless type, with the present improvements applied thereto. Fig. 2 is a plan view. Fig. 2^a is a detail. Fig. 3 is a sectional view of the dogless head showing, however, in side elevation a portion of the knitting head. Fig. 4 is a detail sectional view of the dogless head substantially on the line 4-4 of Fig. 2. Fig. 5 is a view of a detail of a part of the let-off connection.

In these drawings, 1 is the rotary cam box, and 2 the rotary dial cap, 3 is the post to which the needle dial 4 is attached, 5 is the fixed needle cylinder. A frame or plate 6 having a hub 7 surrounding the dial post is formed with or fixed to the yoke arms 8, attached to the posts 9, supported on the revolving cam box. This plate carries the thread guides consisting in the particular construction shown of the openings 10. Surrounding the revolving plate 6 and supported thereon is a ring 11, which is substantially a fixture, it not partaking of the rotation of the plate 6 and other parts but being connected to the fixed frame. Its con-

nexion with the fixed frame may vary, but in the particular construction shown, we employ an arm 12, Figs. 2 and 3, extending therefrom to a post or shaft 14 mounted in the bracket 15, suitably attached to the fixed base of the machine. The arm 12 bears against the top of the post or shaft and prevents the ring or frame 11 from rotating with the knitting head, the direction of rotation of the latter being indicated by the arrow X. For purposes of adjustment of the ring in relation to the dial post, dial and cylinder, the arm 12 is connected with the ring pivotally at 16, and stop bolts 17 adjusted in ears 18 of the arm 12 bear on the ring. The dial post is attached to this fixed ring by sliding locking dogs 19, though we show these merely by way of example. These dogs slide in recesses 20 of the depending rim of a plate 21, which is keyed at 22 to the dial post. A cap 23 screwed on the hub of the cap plate furnishes a support for the dial post, a pin or pins 24 thereon bearing on the cap.

The sliding dogs are retracted in succession to allow the thread to pass in revolving with the knitting head, and for this purpose the dogs have depending pins 25 entering a cam groove or depending into position to be acted on by the cams 26 forming said cam groove. When the dogs are all the way out they engage notches 27 in the ring 11, and thus they form the connection between the fixed frame ring 11 and the dial post to hold the latter against rotation while the needle cams rotate. When, however, the cams 26, which are fixed to the revolving plate 6, arrive at one of the locking dogs, this is forced radially inward, leaving an opening between its end and the fixed ring through which the thread which revolves with the machine may pass, this opening being indicated at 10', and 10" indicating the thread guide opening through the cam piece which registers with the thread guide opening 10 of the plate 6. The revolving bobbin stand 28 has its ring 28' supported by the fixed cap plate 21, said ring being pinned at 28" to the plate 6, Fig. 2.

All of the parts above described are substantially the same as those disclosed in the patent above referred to, they being described herein as an example of one type of

80

110

machine to which the invention may be applied. Parts of our present invention have been devised particularly for their association or combination with parts of the dogless head above described, as will appear in the following description. We wish it understood that while a part of our present invention, in one aspect, relates to this association or combination, we do not limit ourselves in this respect except as set forth in some of the appended claims, and we will point out later, herein, one example of how our invention may be applied to machines of a different type.

In the particular machine chosen to illustrate our invention, a let off ring 29 is supported on the fixed frame ring, being centered by a shoulder 11^x of said frame ring and being held against upward displacement by the lip 30 of the bobbin stand ring. This let off ring is normally at rest but it is moved circumferentially when the thread fails or breaks or when a snarl or bunch occurs at the needles by a dog 31 pivoted in a stud 32 projecting from the revolving bobbin stand ring 28^y. Normally this dog rests by gravity or is spring held in the position shown in Fig. 4. It is moved downwardly to engage any one of the studs 29^x on the let off ring when operated either by the rotary rod 33 leading to the overhead stop motion or by the sliding rod 34 leading to the needle detector 35. When this engagement takes place the let off ring is moved circumferentially because the dog is carried by the revolving bobbin stand, and one of its projections 29^y will now operate the arm 36, which through the connections hereinafter described, will operate the let off clutch, if such form of let off is used. The rock shaft or rod 33 is mounted in the revolving bobbin stand and it has fixed to its lower end an arm 37 having a pin and slot connection (Fig. 2) with a rod 38 slidably mounted in the bobbin stand, and which when moved radially outward will operate the dog 31 as above described, to cause the rotary movement of the let off ring. The arm 37 is provided with a handle by which the overhead stop motion may be reset.

The needle detector comprises a depending finger 35 pivotally mounted at 39 to the bracket 40 fixed on the dial cap and connected by a link 41 with an arm 42 mounted on a shaft 43, journaled in the bracket Fig. 3, said shaft being under tension of a spring 44. This spring tends to turn the arm 42 downwardly, but when the detector finger is upright, as shown in Fig. 1, the relation of the pivots of detector link and arm are such that the detector will remain in this position until its lower end strikes an obstruction such as a bunch, snarl or bent needle when its lower end will swing leftward carrying the upper pivot 49 to the right so

that the spring will now act and complete the movement of the detector and this will cause the arm 50, fixed on the shaft 43 to rise and lift the rod 34 resulting in throwing the dog 31 into engagement with the let off ring 29. The rod 34 is carried by the revolving parts of the head. It may be here stated that with a dogless form of knitting head the let off ring is immediately combined with the frame ring 11, forming a part of said head, but where the invention is applied to a different type of machine the let off ring may be otherwise mounted on a suitably fixed upper frame member. As an instance of another type of machine with which the invention may be used, we would mention that one in which dogs are employed between the needle cylinder and dial.

Referring now to the connections leading to the left off device, i. e. the clutch, when such is used, these include the rock shaft 51 pressed by a spring 52, so that a stop arm 53 on the head 54, fixed to the said shaft, will bear normally against a stop pin 55, Fig. 2 and maintain the arm 36 in the position shown. The rock shaft 51 is mounted in a bracket 56 fixed to the base of the machine. The head 54 carries a pin 57 which overlies a latch 58, pivoted to the bracket portion 56. This latch restrains the arm 59, pivotally mounted on the bracket at 60, and under tension of a spring 61. The arm at its outer end is provided with a tooth 62 under tension of a spring 63, said tooth engaging a shoulder or tooth 64 on the latch. This arm 59 is adapted to operate a lever 65, when said arm is released by the latch 58 and is free to turn under the pressure of its spring. The lever 65 is pivotally connected by a link 66 with a lever 67 which has a pin lying in a groove of the pulley hub 69, the said lever 67 being pressed by a spring 68. With the parts in the position shown in Fig. 2, the members of the clutch are in engagement as shown at 70, the lever 65 being held in the position indicated by the stop pin 71 thereon bearing against the stop spring 72. Supposing now that the let off finger or arm 36 is operated, the pin 57 will be removed from over the latch 58 and the spring 61 will then exert its force, throwing the arm 59 to the left in Fig. 5, and bringing a projection 73 of said arm against a pin 74 of the lever 65, thus turning the said lever on its pivot 75, which results in drawing upon the link 66 and turning the lever 67 in proper direction to withdraw the clutch pulley from the member of the clutch which is fixed on the drive shaft, the pulley then running loosely with its clutch member and the machine coming to rest. The lever 65 may be operated by either of the handles 76. It will be noted that the pin 74 stands off slightly from the projection 73 of the striking arm so that this arm 130

will not strike the pin 74 until after it has performed a part of its stroke. In resetting the parts it is only necessary to turn the lever 65 in the direction of the arrow

5 Fig. 2, the pin 74 thrusting the arm 59 back so as to be engaged by the gravity latch and the spring stop 72 permitting the lever to have a full movement beyond the position shown in Fig. 2. When pressure on the 10 lever is released, however, the spring stop 72 will bring the lever to the position shown in said Fig. 2. Any suitable form of brake may be employed, such for instance as a 15 brake block, indicated in dotted lines at 77, upon which bears a block 78 pivotally mounted on the lower end of the stem of the arm 59 so that as this arm is turned the block 78 will press upon the block 77 and throw this against the edge of the revolving 20 portion of the knitting head. The gravity latch has a tooth at 64', and when the tooth 62 of the striking arm 59 is in engagement with the tooth 64' the brake will be held off from contact with the knitting head so 25 that this may be rotated freely by hand, it being understood that at this time the clutch 70 is out of engagement. With the parts in the position shown in Fig. 2 it will be noticed that the centers 75, 71 and 71' are 30 out of line, and thus the parts will be locked in this position and it will be necessary to move the center 71 across the line of the centers 75 and 71' in order to allow the spring 68 to act in releasing the clutch.

35 It will be seen that by reason of the pin 74 of the hand lever being located at some distance away from the face of the projection 73 of the striking arm 59 that the hand lever can turn in the direction of the arrow 40 and this motion will be sufficient to release the clutch by hand the spring 72 yielding for this purpose but bringing the parts back to the position shown when pressure of the hand lever is released. By this the clutch 45 can be thrown out without it being necessary to throw the hand lever to the reverse position from that shown in Fig. 2.

Reverting to the needle detector, it will be seen from Figs. 1 and 3, that this depends normally in substantially vertical 50 position down along the side of the dial cap and it is pivoted to swing substantially in the direction of the needle row leftward from this vertical position when it strikes a 55 snarl or bunch. It is rendered extremely sensitive because, however slight its movement from a vertical position the spring 44 will be rendered effective to throw the detector finger all the way to the left in Fig. 60 1, so that it will clear the obstruction and at the same time the arm 50 will be thrown up against the rod 34 to operate the let off connections. The movement necessary to bring the spring 54 into full play need only 65 be sufficient to move the center 44 out of

line with the pivot of the finger and the pivot connection between the link 41 and the arm 42.

We claim:—

1. In combination with a knitting machine having a fixed needle carrier, a let-off connection comprising a normally stationary ring surrounding the axis of the knitting head, a pivoted dog revolving with the knitting head and independent of contact with the thread, a needle detector and a stop motion with connections therefrom for operating the said pivoted dog positively to effect engagement of said dog with the ring, a let-off device and connections between the ring and the let-off device to operate the latter when the ring is moved by the dog, substantially as described. 70

2. In combination in a circular knitting machine, having a fixed needle carrier and revolving cams, a ring arranged concentric with the knitting head, and normally at rest, a needle detector, a connection leading from a stop motion, a member revolving with the movable part of the knitting head, engagement between the said member and the ring being effected by either the stop motion connection or the needle detector, substantially as described. 85

3. In combination in a circular knitting machine, having a fixed needle carrier and revolving cams, a ring arranged concentric with the knitting head, and normally at rest, a needle detector, a connection leading from a stop motion, a member revolving with the movable part of the knitting head, engagement between the said member and the ring being effected by either the stop motion connection or the needle detector, said ring being located above the needle 100 head and connections leading up from the needle detector to the said member, substantially as described. 90

4. In combination in a circular knitting machine, a fixed cylinder, dial and dial post, a fixed frame ring surrounding the dial post, a rotary yarn carrier together with shifting locking means for the dial post, located within the frame ring, and connecting the same with the dial, a bobbin 110 stand surmounting the frame ring and the said parts within the same, a let-off ring also surmounting the frame ring and surrounding the bobbin stand, a device external to and moving with the bobbin stand for 115 engaging the let-off ring, means controlled by the yarn or knitting to control the said device, and connections operated by the said let-off ring, substantially as described. 120

5. In combination with a knitting machine, a pivoted needle detector finger, a spring pressed arm and a link connection between the spring pressed arm and the finger, the pivotal points between the link and the arm and detector being substantially 125 130

1. in line when the detector finger is in operative position to hold the spring against action, said spring acting when the finger is removed from its normal position, substantially as described.
2. In combination with a knitting machine, a needle detector finger, pivotally mounted, a rock shaft, a spring for operating the rock shaft, an arm on the rock shaft, a link connecting the arm with the detector finger, the pivots of the detector finger, link and arm being in line when the detector finger is in normal position, an arm on the rock shaft and let-off connections operated by the said arm, substantially as described.
3. In combination in a circular knitting machine, a normally stationary let-off ring having a series of projections, a latch carried by a rotary part of the machine to engage any one of said projections to revolve the ring, stop motion connections for operating the latch, and let-off connections operated by the ring, one part of said stop motion connections consisting of a radially movable rod, a vertical rock shaft, a connection between said rock shaft and rod, said parts leading to connections overhead, and a needle detector with a vertically mov-
- able rod between the same and the latch, said latch being operated either by the radial movement of one rod or the vertical movement of the other, substantially as described.
4. In combination in a circular knitting machine having a fixed needle carrier and revolving cams, a ring arranged concentric with the knitting head, and normally at rest, a pivoted dog carried on and revolving with a movable part of the knitting head, said dog having a portion to engage and move the ring, a vertically sliding rod to operate the dog, a horizontally sliding rod also arranged to operate the pivoted dog, a stop motion connection for operating the horizontal rod, needle detector mechanism for operating the vertical rod, and let-off connections operated by the movement of the ring, substantially as described.
5. In testimony whereof, we affix our signatures in presence of two witnesses.
